(57) **CLAIM**

The ornamental design for a carry bag for outboard motor as shown and described.

DESCRIPTION

FIG. 1 is a side perspective view of a carry bag for outboard motor, shown without environmental structure, and with surface shading, according to our new and ornamental design.

FIG. 2 is a left side view thereof.

FIG. 3 is a right side view thereof.

FIG. 4 is a front view thereof.

FIG. 5 is a rear view thereof.

FIG. 6 is a top view thereof.

FIG. 7 is a bottom view thereof.

FIG. 8 is a side perspective view of the carry bag for outboard motor shown with environmental structure, and with surface shading.

FIG. 9 is a left side view thereof.

FIG. 10 is a right side view thereof.

FIG. 11 is a front view thereof.

FIG. 12 is a rear view thereof.

FIG. 13 is a top view thereof.

FIG. 14 is a bottom view thereof.

FIG. 15 is a side perspective view of the carry bag for outboard motor, shown without environmental structure, and without surface shading.

FIG. 16 is a left side view thereof.

FIG. 17 is a right side view thereof.

FIG. 18 is a front view thereof.

FIG. 19 is a rear view thereof.

FIG. 20 is a top view thereof.

FIG. 21 is a bottom view thereof.

(Continued)

FIG. 22 is a side perspective view of the carry bag for outboard motor, shown with environmental structure, and without surface shading.

FIG. 23 is a left side view thereof.

FIG. 24 is a right side view thereof.

FIG. 25 is a front view thereof.

FIG. 26 is a rear view thereof.

FIG. 27 is a top view thereof; and,

FIG. 28 is a bottom view thereof.

The broken lines showing the outboard motor in FIGS. 8-13 and 22-27 depict environmental structure and form no part of the claimed design. The remaining broken lines illustrate portions of the carry bag for outboard motor that form no part of the claimed design.

1 Claim, 28 Drawing Sheets
